UNITED STATES PATENT OFFICE.

JAMES HART TAYLOR AND JULIUS BYRON TAYLOR, OF TOLEDO, OHIO.

MOP-WRINGER.

1,079,454.

Specification of Letters Patent.

Patented Nov. 25, 1913.

Application filed November 22, 1911. Serial No. 681,751.

To all whom it may concern:

Be it known that we, JAMES H. TAYLOR and JULIUS B. TAYLOR, citizens of the United States, residing at Toledo, in the county of Lucas and State of Ohio, have invented certain new and useful Improvements in Mop-Wringers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to that class of mop-wringers in which a pail has mounted in its open upper end a wringer-roll opposed to another wringer-roll journaled in guides or ways and movable into and out of operative position by means of a foot-lever, and is designed to furnish a construction which shall be cheap, simple, strong and durable.

Our invention is also designed to provide roll-supports which will permit the rolls to readily accommodate themselves to irregularities in the mop.

Our invention also relates to certain details of construction hereinafter described, and pointed out in the claims.

We attain the objects above indicated by means of the construction and arrangement of parts hereinafter described, and shown and illustrated in the accompanying drawings, in which,

Figure 1 is a perspective view of our mop-wringer, parts of the upper edge of the pail hereinafter referred to being broken away to disclose the roller bearings and pivots hereinafter referred to, and Fig. 2, a like view of the pair of rolls, hereinafter referred to, detached.

Corresponding parts are represented by like numerals in both views.

In the drawings, 1 is a mop-pail having secured in opposite sides of its mouth, as at 2, two horizontal parallel bars 3 having longitudinal slots 4. At one end of and between these two bars are pivoted, midway between their ends as at 5, opposed link-bars 6. Between the upper ends of these link-bars the holes for the pivots being shown at 5. Fig. 2 is journaled, as at 7, a wringer-roll 8 and between their lower ends is journaled, as at 9, a wringer-roll 10. The ends of the shafts of these two rolls project far enough

to contact with the top and bottom of the bars 3 when the links 6 are swung on their pivots, so that the shafts of the two rolls are at all times held one above and the other below the bars 3. The two links 6 have a movement on their pivots 5 independently of each other so that the axes of the two rolls may have a limited swing into and out of the same plane, as illustrated in Fig. 2.

11 is a third wringer-roll having a shaft 12 which at opposite ends projects through the slots 4 in the bars 3. When a mop is to be wrung, it is suspended from the mop-stick between the roll 11 and the other two rolls. Now the roll 11 is moved in the slots 4 so that the mop is tightly squeezed between the roll 11 on one side and the pair of rolls on the other side. Next the mop, thus squeezed, is pulled out between the rolls and thus the wringing is effected. The play of the link-bars 6 on their pivots permits the rolls 8-10 to accommodate themselves to inequalities in the mop. This forward movement of the roll 11 in the guides 4, as well as its retreat, is accomplished by means of the devices now to be described.

A U-shaped member 13, having its arms curved downwardly and which we term a "fork," is connected at the extremities of its arms with the extremities of the shaft 12. The fork at its middle has a horizontally projecting arm 14, pivoted, as at 15, between jaws forming a vertical opening in the top of a lever 16. This lever is curved downwardly and outwardly, as at 17, and is fulcrumed, as at 18, upon the outer end of bracket 19, rigidly secured, as shown, to the side of the pail.

20 is a foot-lever fulcrumed, as at 21, upon bracket 22 rigidly secured through bracket-plate 22^a to the side of the pail. The lever 20 is bifurcated or slotted, as at 23, and through its opening passes the curved portion 17 of the lever 16. Between the two sides of the slot 23 is journaled, as at 24, a roller 25 which rides upon the upper surface of the curved part 17. Now, when the operator stands with one foot upon the foot-piece 26 and places his other foot upon the pedal 27 of the lever 20, the roller 25 rides upon the top of the curved part 17, swinging the lever 16 upon its fulcrum and drawing the fork 13 and the roll 11 over into operative relation with the pair of rolls 8-10. The roll 11 is restored to its normal or open position by means of a spring 28 consisting

of a piece of stout spring-wire bent upon itself at its middle, the two arms thus formed being coiled, as at 29. The two extremities of the spring are firmly held in vertical openings in lugs 30 formed upon the bracket plate 22*. The bight of the spring presses against the outer side of the lever 16 above its fulcrum and thus holds the fork and roll 11 in the position illustrated in the drawing.

Having described our invention, what we claim and desire to secure by Letters Patent is,

1. In a device of the described character, a pail, a bracket secured to the side of the pail, an upright lever of the first class fulcrumed upon said bracket and having at its lower end a downwardly outwardly curved portion, a fork pivotally connected with the upper end of said lever, a wringer-roll having the ends of its shaft mounted in the fork, a pair of parallel bars in the mouth of the pail which slidably support the ends of said shaft, a pair of link-bars pivoted respectively upon said bars, a pair of rolls journaled upon and between said link-bars, a lever of the second class fulcrumed upon the side of the pail and be-

low said bracket and having at its outer end a pedal, a roller carried by said second lever and which rides upon the top of the said curved part of the lever first mentioned, and a spring which holds the upper part of the lever first mentioned pressed toward the pail.

2. In a device of the described character, in combination, a pail, an upright lever fulcrumed on the side of the pail and having at its lower end below its fulcrum a downwardly, outwardly curved arm, a foot-lever fulcrumed on the side of the pail and carrying a roller which rides upon the top of said curved arm, opposed rolls in the mouth of the pail, and a forked member having its arms connected with the opposite ends of one of said rolls and having its outer end pivotally connected with the upper end of said upright lever.

In testimony whereof we affix our signatures in presence of two witnesses.

JAMES HART TAYLOR.
JULIUS BYRON TAYLOR.
